UNITED STATES PATENT OFFICE

1,935,876

CHARGE CAR FOR FEEDING MATERIAL TO
BE SINTERED

John E. Greenawalt, New York, N. Y.

Application April 27, 1931. Serial No. 533,149

10 Claims. (Cl. 214—18)

My invention has relation to improvements in traveling hoppers, or charge cars, especially adapted for feeding material into the holder, or pan, of a sintering apparatus for the purpose of sintering the same. This invention is more particularly an improvement over that described in the patent granted to Thomas M. Alexovits on May 19, 1931, Patent No. 1,806,438.

The principal object of the present invention is to provide means for discharging the material from the hopper in a regulated stream of non-uniform density. That is, there will be a series of zones across the width of the stream in which there will be little or no material. The advantage of having these thin spots, or zones, in the material stream is to improve the condition of the charge, produced by the flow of material into the pan, so as to cause the charge to sinter more rapidly and more perfectly. The effect of such non-uniform flow of material on the sintering charge is considered in detail in my process application filed of even date herewith, and now Patent No. 1,888,458. This application is concerned only with the means of obtaining such effect.

The manner of accomplishing the above object, as well as realizing other advantages inherent in the invention will be better apparent from a detailed description of the invention in connection with the accompanying drawings in which:

Figure 1 is a top plan of my improved charge car with parts broken away; Fig. 2 is a vertical longitudinal section taken on the line 2—2 of Fig. 1 with the upper part of the hoppers broken away; Fig. 3 is a cross-sectional detail taken on the line 3—3 of Fig. 2; and Fig. 4 is a diagrammatic section taken on the same plane as section 3—3 but looking toward the breaker roll for separating the particles of finely divided material as it is being fed into the sintering pan; Fig. 5 is a fragmentary view showing in vertical section a modified form of the invention wherein the finger adjacent the breaker roll and support therefor is mounted for vibratory motion; Fig. 6 is an enlarged horizontal fragmentary section taken on the plane indicated by the line 6—6 of Fig. 5; Fig. 7 is a cross-sectional detail taken on the line 7—7 of Fig. 6; Fig. 8 is a cross-sectional detail taken on the line 8—8 of Fig. 6, and Fig. 9 is a top plan of the knife edge bearing for the channel supporting the means for interrupting the material stream.

Referring to the drawings C represents my improved charge car comprising a truck frame F, the side members 1, of which are connected by a

series of cross-channels 2, 2 etc. The frame F carries a hopper H for the finely divided material m that is to be sintered, and a hopper H' for the coarser material m' that is to serve as a bed on which the material m is disposed. The frame F is carried on wheels W, W' affixed to journals 3, 3' mounted in journal boxes 4, 4' secured to the frame F in the usual manner. The car C is driven by a motor M mounted on frame platform 5 through the reducing gear set 6 connected between motor shaft 7 and rear journal 3.

The mechanism for feeding the material m, m' from hopper H and H' is similar to that employed in the charge car described in the patent granted to Thomas M. Alexovits, above mentioned and comprises a feed roll 8 mounted below the open bottom of hopper H on shaft 9 and a feed roll 10 mounted below the open bottom of hopper H' on shaft 11. Hoppers H and H' also have discharge orifices 12 and 13, the flow of material through which is controlled by gates 14 and 15 respectively. The operation of these gates is similar to that of the construction described in the patent aforesaid, and is not illustrated or described in detail. On each side of hopper H extending downwardly from the end of orifice 12 is a side plate 16 to prevent the flow of material m from spreading laterally after passing through the orifice. The plate 16 is connected (as shown in Fig. 3) to the side member 1 and to a cross-channel 17 which extends cross-wise beneath feed roll 8 and is supported at each end by an angle and plate construction 18 (shown in Fig. 3). A breaker roll 19, the surface of which is covered with a plurality of bosses 20, is mounted on the shaft 21 below and slightly forward of the feed roll 8 so as to receive the material m after it passes over said feed roll, and a series of fingers 22 are secured to channel 17 in uniformly spaced relation and project toward and in close proximity to the periphery of the breaker roll 19. These fingers 22 extend along the channel 17 for a distance equal to the width of the breaker roll 19 and will intercept the stream of material as it flows from the breaker roll.

The feed roll 8 is caused to rotate in the direction of the arrow by connecting its shaft 9 with a gear 23 on journal 3 through a train of gears mounted in gear case 24 in a manner similar to the operation of the feed roll in the patent aforesaid. The breaker roll 19 is driven in a direction opposite to the direction of rotation of feed roll 8 by a motor M' and reducing gear 25, the latter being connected to a sprocket wheel 26 through sprocket chain 27, 110

travelling over the wheel 26 and a sprocket pinion 28 mounted on the end of shaft 29 leading from the reducing gear set 25.

The feed roll 10 is also rotated in the direction 5 of the arrow by a gear 30 through a train of gears mounted in gear housing 31. As in the patent above referred to, the gates 14 and 15 are actuated through the same mechanism that actuates the feed rolls 8 and 10, said 10 mechanism not being herein described in detail as it is not a part of the present invention. The present invention is concerned specifically with the breaker roll 19 and fingers 22 associated with it for the purpose of providing void spaces in the 15 stream of material before said material is deposited in the sintering pan.

The manner in which the material is discharged into the sintering pan P may be understood by referring to Fig. 4, which shows the material *m* falling from the breaker roll 19 in a wide stream extending from end to end of said roll. The fingers 22 are shown in front of said roll where they intercept the material stream and produce gaps *g* therein from one side of the 25 stream to the other. Therefore, no material will fall into the sintering pan P where these gaps are. However, the coarser particles of material in the stream will roll over into the gaps from the deposits immediately adjacent to the gaps 30 according to the laws of rolling friction. Thus, when the pan is charged with a bed of the desired thickness, this bed *b* of material will contain regularly spaced zones *z* of coarser material and, of course, greater porosity. These zones *z* 35 throughout the bed *b* are responsible for a quicker sintering action, as explained in detail in my co-pending application on "Methods of constituting a charge of material to be sintered".

It may be desirable, particularly in treating 40 certain materials, to arrange the fingers 22 so that a vibratory motion may be imparted to them. Vibrating these fingers will not only help to prevent material from adhering to them, but will also help in creating uniformity of the 45 zones and leave the surface of the charge in better condition for ready ignition. In Figs. 5 to 9 inclusive I show one method of arranging the fingers so that they will be capable of vibration.

50 By referring to Figs. 5 and 6 it will be seen that the fingers 22' are fixed as before to a channel 17', but the channel 17' is not rigidly fixed to the charge car frame. The channel is loosely mounted on studs 32, 32 traversing the angle 55 iron 18' depending from the car frame, and there are coil springs 33, 33 disposed on the studs between the channel 17' and angle iron 18', which springs force the channel outwardly against a knife edge bearing 34 disposed between studs 32, 60 32 and fixed in place on the angle iron 18' by a stud 35 which traverses an opening 35' in channel 27'. This supporting arrangement with a channel 17' is provided at both ends of the channel and intermediate the spring supports 65 there are a series of bearings 36 for a shaft 37. One end of the shaft carries a sprocket wheel 38, over which a chain 39 passes, said chain also passing over a sprocket 40 on shaft 29. Thus, when the shaft 29 rotates to drive the breaker 70 roll 19 the shaft 37 will also be driven. An eccentric weight 41 is disposed on shaft 37 adjacent to each of the bearings 36, so that when shaft 37 is rotated the weights will tend to cause it to oscillate and impart a vibratory motion to 75 the channel 17', and of course, the fingers 22'

projecting therefrom. In order to permit this vibratory motion, the channel 17' is connected to the plate 16' (which plate corresponds with plate 16 in the main form) by means of a bolt 42 having clearance through the opening 43 in the plate. Obviously, there are other ways of causing the fingers 22' to vibrate, and I do not wish to restrict myself to the specific details of construction herein shown.

Having described my invention, I claim:

1. In a charge car, a holder for the material to be charged, means below said holder for loosening and lightly depositing the material discharged from the holder, and means in close proximity to the supporting surface of the holder for blocking the flow of material at a plurality of points after the material passes the loosening means.

2. In a charge car, a holder for the material to be charged, means below said holder for feeding the material onto a suitable support, and deflecting means for dividing the material after it leaves the feeding means into a plurality of juxtaposed streams, said means being sufficiently close to the supporting surface to keep the 100 material separated until being deposited on said surface.

3. In a charge car, a holder for the material to be charged, discharge means associated with the holder, and baffles for dividing the discharged 105 material into a plurality of juxtaposed streams, said baffles being sufficiently close to the supporting surface to keep the material separated until being deposited thereon.

4. In a charge car for finely divided material, 110 a holder for the material to be charged, a feed roll below said holder, means for fluffing the material after it leaves the feed roll, and baffles for dividing the fluffed material into a plurality of juxtaposed streams, said baffles being sufficiently close to the supporting surface to keep the 115 material separated until being deposited thereon.

5. In a charge car, a holder for the charge, said holder having an open bottom, a feed roller disposed below said open bottom, an agitator adjacent to said feed roller, and baffles for dividing the material after it leaves the agitator into a plurality of juxtaposed streams, said baffles being sufficiently close to the supporting surface 120 to keep the material separated until being deposited thereon.

6. In a charge car, a holder for the material to be charged, a feed roller below said holder adapted to assist the flow of material therefrom, 130 means for confining the material stream within definite limits, and baffles between the confining means and below the feed roller, said baffles being of a sufficient width to effectively divide the discharged material into a plurality of juxtaposed streams.

7. In a charge car, a holder for the charge, said holder having an open bottom, a feed roller disposed below said open bottom, a fluffing roll adjacent to said feed roller, and baffles below 140 said fluffing roll for intercepting the material stream at a plurality of points, said fluffing roll having on its surface a plurality of formations for separating cohering particles of material and said baffles being of sufficient width and sufficiently close to the holder to effectively divide the discharged material into spaced streams.

8. In a charge car, a holder for the material to be charged, discharge baffles associated with the holder, means for dividing the discharged 145 material

material into a plurality of juxtaposed streams, and means for vibrating said baffles along the longitudinal axis of the baffles.

9. In a charge car for finely divided material, 5 a holder for the material to be charged, a feed roll below said holder, means for fluffing the material after it leaves the feed roll, and vibratory baffles for dividing the fluffed material into a plurality of juxtaposed streams, said baffles being of sufficient width and sufficiently close to the holder to maintain the streams divided until being deposited in said holder.

10. In a charge car, a holder for the charge, said holder having an open bottom, a feed roller disposed below said open bottom, a fluffing roll adjacent to said feed roller, means below said fluffing roll for intercepting the material stream at a plurality of points, said fluffing roll having on its surface a plurality of formations for separating cohering particles of material, and means for vibrating said intercepting means. 80
